[57] CLAIM

The ornamental design for an envelope package dispenser,
as shown and described.

DESCRIPTION

FIG. 1 is a perspective view of an envelope package dispenser showing my new design;

FIG. 2 is a front elevational view thereof;

FIG. 3 is a top plan view thereof;

FIG. 4 is a right side elevational view with the left side being
a mirror image thereof;

FIG. 5 is a rear elevational view thereof;

FIG. 6 is a bottom plan view thereof; and,

FIG. 7 is an environmental left elevational view thereof.

The broken line showing of the packets, interior wall, and
human hand in FIG. 7, is for illustrative purposes only and
forms no part of the claimed design.
